UNITED STATES PATENT OFFICE

2,059,638

LIQUID FUEL BURNER

Hermann Guhl, Friedrich Wilhelm Oscar Dorl,
and Karl Gargel, Karlsruhe in Baden, Germany,
assignors to Junker & Ruh A.-G., Baden,
Germany, a corporation

Application April 2, 1932, Serial No. 602,850
In Germany April 20, 1931

3 Claims. (Cl. 158—81)

The present invention relates to a preheating and vaporizing device for burners which are operated with a liquid fuel supplied under pressure.

Preheating and vaporizing devices for liquid fuel burners have been known heretofore, but such known preheating and vaporizing devices have given unsatisfactory operation and were the source of constant difficulty and defectiveness of operation. Consequently, the use of such known burners was not only inconvenient and an annoyance, but actually involved a fire hazard to the user.

The liquid fuel burner unit comprising the preheating and fuel feeding arrangement according to the present invention will avoid these disadvantageous features of the known devices.

It is the object of this invention to provide a liquid fuel burner unit in which the fuel is fed in the manner of an injector and in which the inlet aperture for the liquid fuel is smaller than or at least not greater than the aperture for the jet flowing from the vaporizing element.

It is a further object of this invention to provide a liquid fuel burner unit in which a separate fuel containing chamber is provided for containing the fuel necessary for the preheating of the burner before starting the operation.

A further object is the provision of larger surfaces for attaining the necessary volatilization of the liquid fuel in successive steps and further providing the vaporizing element with a dirt separator and cleaning device for the nozzle to prevent clogging of the said nozzle.

A further object is to provide the burner unit with special arrangements for supplying the burner with sufficient primary and secondary air for substantially complete combustion and further the arrangement of parts to prevent back-flashing of the burner flame.

Other objects and advantages will appear in the following specification, reference being had to the accompanying drawings, in which:

Fig. 1 is a diagrammatic illustration in side elevation showing a vaporizing element provided with a separate injector in the fuel supply line;

Fig. 2 is a similar view of another modification in which the fuel supply line is provided with an opening and a construction in the line below the opening;

Fig. 3 is a diagrammatic illustration of a third modification of the vaporizing element in which the aperture in the fuel line is disposed on the inner side of a curved portion of the line;

Fig. 4 is a similar view of a fourth modification of the vaporizing element in which the aper-

ture in the fuel line is disposed on the outer side of the curved portion of the fuel line;

Fig. 5 is a diagrammatic view of a vaporizing element and its relationship to the burner and fuel containers;

Fig. 6 is a diagrammatic view similar to Fig. 5 in which the preheating-fuel vessel is positioned above the fuel reservoir;

Fig. 7 is a similar view to Fig. 6 in which the preheating-fuel vessel is positioned below the fuel reservoir;

Fig. 8 is a perspective view of a small cooking plate equipped with the applicant's invention;

Fig. 8a is a perspective view of the cooking plate shown by Fig. 8, taken from another angle. 15

Referring first to Fig. 5, 1 is the injector tube which is U-shaped and has an open limb 2. The other limb 3 passes by way of a closure valve for example a tap 9 to the vaporizer 4 which discharges at the jet 5 into the mixing tube 11 provided on the burner 12. The burner 12 is disposed beneath the vaporizer 4 so that its flame heats the vaporizer.

The U-shaped tube 1 has an aperture at 6 which is smaller than or at the most equal to the aperture of the jet 5 of the vaporizer 4. The U-shaped pipe 1 is disposed in a separate chamber 15 which in the embodiment according to Fig. 5 is disposed immediately adjacent the fuel reservoir 13 and is connected therewith by means of a pipe 17. The pipe 17 discharges at 18 into the preheating fuel chamber 15. This vessel is also connected with an air pump 14. 25 30 35

The mode of operation of the arrangement is as follows. The fuel reservoir 13 and also the preheating fuel chamber 15 by way of the pipe 17 are first partly filled with the appropriate fuel. Then by means of the air pump 14 air under pressure is forced into the preheating fuel chamber 15 so that the liquid is displaced through the pipe 17 into the fuel reservoir 13 which is also under pressure. In this way the liquid level in the preheating fuel chamber sinks to the level and rises in the fuel reservoir 13 to the level b—b. If now the valve 9 is opened then the compressed air in the chamber 15 passes through the pipe 2 and the pipe 3 into the vaporizer 4 and in so doing conveys with it the fuel vapors which are in the preheating fuel chamber as well as a certain quantity of liquid. The gas-air mixture passes through the nozzle 5 into the burner 11 and is ignited at the burner head 12. 40 45

Due to the escape of the compressed air the liquid level in the preheating fuel chamber 15 again rises whereby at the same time the liquid passes 50 55

through the pipe 17 from the reservoir 13 until finally the liquid level in the chamber 15 reaches the level *c-c* whereas the liquid level in the reservoir 13 assumes the position *d-d*. However, in this way the liquid closes the inlet for further air to the pipes, 1, 2 and 3, and now only liquid passes through the pipe 3 into the vaporizer 4 and there is vaporized and then passes as gas or as gas-air mixture to the burner 12.

10 As only a very small quantity of gas-air mixture is necessary to light the burner it is possible to utilize the same for heating the vaporizer for the continuous operation.

If the burner is to be rendered inoperative then 15 all that is necessary is to close the valve 9 to suspend the supply of fuel. Vaporization is thereby terminated and the flame of the burner 12 goes out.

To set the apparatus in operation again it is 20 frequently necessary to supplement the compressed air in the preheating fuel chamber by one or two short strokes of the pump in order to render the burner ready for operation and on opening the valve 9 the burner can be ignited 25 at 12.

Fig. 1 shows schematically another construction of the injector pipe. Here a separate injector chamber 7 is provided at the lower end of the pipe 1, the pipe 2 which leads to the air space 30 of the preheating fuel chamber 15 projecting into the chamber 7 at 8. 6 is an inlet aperture for the liquid fuel which aperture is smaller than the outlet aperture of the nozzle 5 provided on the vaporizer 4. In this case also the pipe 3 is provided with a control device 9.

In the embodiment according to Fig. 2 the U-shaped pipe 1 is constricted after the manner of an injector immediately beneath the inlet aperture 6 for the liquid fuel and here again the aperture 6 is smaller than the outlet aperture of the nozzle 5.

In the embodiment according to Fig. 3 the inlet aperture 6 is disposed on the inner curve of the U-shaped pipe 1 while in the embodiment of Fig. 45 it is disposed on the outer curve of the U-shaped pipe, this U-shaped pipe being somewhat circular in form at the bend; otherwise the arrangement is the same as in the constructions above discussed.

50 Fig. 6 shows a construction in which the preheating fuel chamber 15 is disposed above the liquid container 13. The two containers are interconnected by means of the pipe 17.

In the embodiment according to Fig. 7 the preheating fuel chamber 15 is disposed beneath the container 13 and here again the two containers are interconnected by means of the pipe 17. In other respects the embodiments of Figs. 6 and 7 are the same as that of Fig. 5.

60 Finally, Figs. 8 and 8a show the entire arrangement applied to a cooking plate. The preheating fuel chamber 15 is disposed laterally of the container 13 and is connected therewith at 18. The U-shaped tube 1 is provided at the bottom with 65 an inlet aperture 6 for the liquid and one of its ends 2 projects into the air space of the preheat-

ing fuel chamber 15 which is charged with compressed air by means of the air pump 14.

We claim:

1. In a liquid fuel burner unit comprising a burner having a vaporizer heated thereby, the combination of a fuel reservoir, a chamber connected at its lower portion with the fuel reservoir and otherwise permanently unconnected therewith, means for conducting fuel from said chamber to said vaporizer, said means comprising a pipe having an opening in the chamber above the connection of the chamber with the reservoir, means for displacing a predetermined portion of liquid fuel from the chamber to the reservoir by air drawn directly from the outside atmosphere, and a flow control device in said pipe, whereby upon opening of said control device carbureted air in said chamber passes to the burner and upon exhaustion of said air liquid fuel passes to said burner. 20

2. A liquid fuel burner unit comprising a burner having a vaporizer heated thereby, said vaporizer having a restricted opening into said burner, a fuel reservoir maintained under pressure, a chamber connected at its lower portion with the fuel reservoir, means for conducting fuel from said chamber to said vaporizer, said means comprising a U-shaped pipe having one leg opening into the fuel vaporizer, said pipe extending within the chamber and adjacent the bottom thereof and having its other leg opening into said chamber adjacent the top, said pipe having a restricted opening into the chamber at the lower portion thereof, said opening being no larger than the opening from the vaporizer to the burner, means 30 for displacing a predetermined portion of liquid fuel from the chamber to the reservoir by air drawn from the outside atmosphere, and a flow control device in said pipe, whereby upon opening of said control device carbureted air in said chamber passes to the burner and upon exhaustion of said air liquid fuel passes to said burner. 35

3. Apparatus for supplying fuel to a liquid fuel burner in which the burner heats a fuel vaporizer comprising, a liquid fuel reservoir having a permanently closed top and side walls permanently closed at their upper portions, a liquid fuel-air chamber having a connection with the fuel reservoir at their lower portions, means for introducing air under pressure directly from the outside into the upper portion of the fuel-air chamber to put said chamber and reservoir under pressure and force liquid fuel from the chamber into the reservoir whereby the air in the upper portion of the reservoir is compressed and tends to force liquid 45 from the reservoir into the fuel-air chamber, a pipe extending from the vaporizer into the fuel-air chamber, a cut off valve in said pipe, the portion of said pipe in said fuel-air chamber being U-shaped and having an opening in the upper 50 portion of the free leg thereof and having another opening at a lower portion of the pipe in said chamber. 55

CERTIFICATE OF CORRECTION.

Patent No. 2,059,638.

November 3, 1936.

HERMANN GUHL, ET AL.

It is hereby certified that the residence of the assignee in the above numbered patent was erroneously described and specified as "Baden, Germany" whereas said residence should have been described and specified as Karlsruhe in Baden, Germany, as shown by the records of assignments in this office; and that the said Letters Patent should be read with this correction therein that the same may conform to the record of the case in the Patent Office.

Signed and sealed this 12th day of January. A. D. 1937.

Henry Van Arsdale
